CLAIM

The ornamental design for a jar, substantially as shown and described.

DESCRIPTION

FIG. 1 is a top, front, and right side perspective view of my jar;
FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of a portion of the bottom surface is included for the purpose of showing environmental structure that forms no part of the claimed design.

1 Claim, 2 Drawing Sheets**Fig. 1.**

Fig.2.

Fig.3.

Fig.4.

Fig.5.

Fig.6.

Fig.7.

UNITED STATES PATENT AND TRADEMARK OFFICE
CERTIFICATE OF CORRECTION

PATENT NO. : Des. 581,279 S
APPLICATION NO. : 29/293917
DATED : December 18, 2007
INVENTOR(S) : Benjamin Phalan Oates

Page 1 of 1

It is certified that error appears in the above-identified patent and that said Letters Patent is hereby corrected as shown below:

Title page, item [73] Assignee: should read as following: Conopco, Inc. d/b/a Unilever, Englewood Cliffs, NJ

Signed and Sealed this

Sixth Day of January, 2009

JON W. DUDAS
Director of the United States Patent and Trademark Office

UNITED STATES PATENT AND TRADEMARK OFFICE
CERTIFICATE OF CORRECTION

PATENT NO. : Des. 581,279 S
APPLICATION NO. : 29/293917
DATED : November 25, 2008
INVENTOR(S) : Benjamin Phalan Oates

Page 1 of 1

It is certified that error appears in the above-identified patent and that said Letters Patent is hereby corrected as shown below:

Title page, item [73] Assignee: should read as following: Conopco, Inc. d/b/a Unilever, Englewood Cliffs, NJ

This certificate supersedes the Certificate of Correction issued January 6, 2009.

Signed and Sealed this
Third Day of February, 2009

JOHN DOLL
Acting Director of the United States Patent and Trademark Office
